[57] CLAIM

The ornamental design for a railroad brake pipe hanger, as shown.

DESCRIPTION

FIG. 1 is a perspective view, taken from the left side and above, of a railroad brake pipe hanger showing my design it being understood that the broken lines are for illustrated purposes only;

FIG. 2 is a front elevational view thereof;

FIG. 3 is a side elevational view thereof;

FIG. 4 is a top plan view thereof; and

FIG. 5 is a bottom plan view thereof.
